STAUNTON B. PECK, OF CHICAGO, ILLINOIS, ASSIGNEE TO LINK-BELT COMPANY, OF CHICAGO, ILLINOIS, A CORPORATION OF ILLINOIS.

STAND FOR TROUGHING-ROLLS.

1,072,156.

Specification of Letters Patent.

Patented Sept. 2, 1913.

Application filed June 19, 1911. Serial No. 684,150.

To all whom it may concern:

Be it known that I, STAUNTON B. PECK, a citizen of the United States, residing at Chicago, in the county of Cook and State of Illinois, have invented a certain new and useful Improvement in Stands for Troughing-Rolls, of which the following is a specification.

My invention relates to improvements in stands for troughing rolls and is illustrated diagrammatically in one form in the accompanying drawings, wherein—

Figure 1 shows an elevation in part section, and Fig. 2, a detailed plan view with parts removable.

Like parts are indicated by like letters throughout the several figures.

The conveyer belt A is supported upon the five pulleys or rollers A¹, A¹, A², A², and A², each at an angle to the one adjacent to it and mounted respectively upon the short shafts A⁴, A⁴, A⁵, A⁵, and A⁶, which shafts are each provided with axially arranged grease passages A⁷ extending from one end 25 of the shaft and communicating with a centrally located radially arranged discharge passage A⁸. The two outer shafts A⁶ project outwardly from the sleeves B, being held in position therein by the set screws B¹.

The two outer pulleys A¹ are held upon the shafts A⁴ by the collar B² locked in position by the set screws B³. The grease cups B⁴ communicate with the ends of the passages A⁷ in the outer shafts A⁴. The sleeve B is mounted upon the arm B⁵, projecting upwardly and inwardly from the base B⁶, and contains the oil passage B⁷ communicating at one end with the grease cup B⁸ and at the other end with the sleeve B⁹ in which 40 is held the shaft A⁵ by the set screw B¹⁰ in suchwise that the grease passage A⁷ communicates with the passage B⁷. The shaft A⁵ is supported at its other end by the collar C carried by the arm C¹ projecting upwardly from the base C². The bases C² and B⁶ are provided with the opposed upwardly extending lugs C³ and C⁴ having the interlocking surfaces C⁵ and C⁶ and held together by the bolt C⁷. The collar C⁸ projects outwardly from the arm C¹ and supports one end of the shaft A⁶, which shaft is held rigidly in position by the set screw C⁹. The other end of the shaft A⁶ is carried by the collar D, which collar projects outwardly

from the arm D¹, which arm projects upwardly from a similar base C² and is provided with the oil passage D² communicating at one end with the grease cup D³ and at the other end with the passage A⁷, in the shaft A⁶. The bases B⁶, C² from which project the arms B⁵, C¹, form two separate supporting brackets and in order that these brackets may be conveniently lined up and that the shaft A⁶ be held in proper position, they are provided with the opposed lugs C³, C⁴ having the broken, irregular, interlocking surfaces C⁵, which surfaces may be brought closely together by the bolt C⁷ thus insuring a correct alignment and feed of the two sections without the necessity of any careful machining or attention. Each bracket is held in position on the supporting frame by the holding bolts E, E¹ which engage the slots E², E³ in the bases B⁶, C² respectively. The set screws B¹⁰, which hold the shafts A⁶ in position, are placed in the collars B² on the shafts B⁶ in order that they may be more conveniently tightened up to hold the shafts in position. It will be evident that this is the case since this will usually be done before the rollers A¹ are placed in position.

It will be evident that while I have shown in my drawings an operative device, still many changes might be made in size, shape and arrangement of parts without departing materially from the spirit of my invention, and I wish therefore, that my drawings be regarded as in a sense diagrammatic.

The use and operation of my device are as follows: My device which is designed for the support of a conveyer belt is adapted to trough the belt, that is, to raise the sides up above the center in order that loose, finely divided material may be easily carried without waste and spilling. The rolls, which are each mounted on a separate shaft, are lubricated by grease forced through separate grease ducts axially located in the shafts and communicating with radially located discharge passages. Each grease duct is fed from the usual type of grease cup. The outer shafts carry the grease cups at their ends in direct connection with the ducts, whereas the three inner shafts are fed by grease cups which discharge through passages in the brackets, which passages communicate with the grease ducts in the shafts.

In the arrangement shown four brackets are used. These brackets are cast integrally in pairs having one central plane of cleavage between two upstanding lugs. The castings 5 are broken along this line of cleavage making two irregular interlocking surfaces. In setting up the device the central shaft with its roller is first mounted on the two inner brackets. These brackets are bolted in position. The set screw holding the shaft in 10 these brackets is then screwed up before any other rollers are added. The two intermediate shafts with their rollers are then placed in position, being received at one 15 end in the inner brackets and secured at the other end in the outer brackets. The brackets are then brought together in pairs, the broken interlocking parts properly alining them. The outer brackets are then secured 20 to the frame by their proper bolts. The two brackets may then be locked together in pairs if desired by transverse bolts C'. This, however, is not absolutely necessary. The outer shafts are then placed in position and 25 all the set screws fastened down, the outer rolls being placed on their respective shafts. They are held by the outer collars which are locked by set screws and all the grease cups are then attached. The arrangement of the 30 set screws is such that each set screw may be tightened up before the next roller is applied and after this roller is placed in position there will be no opportunity for any one to tamper with the set screws and loosen the

shafts or throw the device out of alinement 35 or adjustment.

Each shaft has a separate and individual greasing apparatus. This is of great importance, especially where there are a series of shafts. Any attempt to supply the grease 40 to a series of shafts through them all will result in excessive grease at some point and an under supply at others.

I employ four brackets each separately secured to the base or support to which they 45 are all attached. In order to aline them properly I cast them together in pairs and then break them apart and they may or may not be held together in this relation by a transverse bolt. I secure the two side intermediate shafts at their outer ends so that 50 they are carried on the outer brackets.

I claim:

A support for troughing rolls comprising 55 a two-part base, rolls supporting arms projecting upwardly from either end of said base, said base being provided with two upwardly projecting lugs, one on either part, said lugs having interlocking surfaces interlocking one with the other, these surfaces being arranged one pair at the lower extremity of the lugs the other pair at the upper extremity, and means for removably holding 60 said interlocking members together.

STAUNTON B. PECK.
